AEROSOL VALVES

Philip H. Sagarin, Bridgeport, Conn., assignor to Valve Corporation of America, Incorporated, Bridgeport, Connecticut

Filed Feb. 2, 1959, Ser. No. 790,505
2 Claims. (Cl. 222—394)

This invention relates to aerosol valves and more particularly to the assembly and mounting thereof, and is an improvement upon Patent 2,772,820 of Dec. 4, 1956 of William R. O'Donnell and assigned to the same assignee as the present invention.

Primarily the present invention contemplates simplification and reduction of the number of parts involved in construction of an aerosol valve.

Likewise the invention proposes utilization of the rigidity of a preformed mounting cup for the location and retention of the valve sealing disk.

A specific object of the invention is to provide a construction wherein the valve sealing disk also functions as a sealing gasket.

Another object of the invention is to more conveniently obtain a final clinching of the valve assembly.

Other objects, advantages and novel structural features of the invention will appear to persons skilled in the art to which it appertains as the description proceeds, both by direct recitation thereof and by implication from the context.

Referring to the accompanying drawing, in which like numerals of reference are used in both views to designate the same parts;

FIGURE 1 is an axial sectional view of a valve assembly incorporating the present invention, showing the valve in its closed condition and showing the assembly mounted in place in a container largely broken away; and

FIGURE 2 is a similar sectional view showing the valve in its open or dispensing position.

In the specific embodiment of the invention illustrated in said drawing, the reference numeral 10 designates an aerosol container of any suitable material and shape adapted to be sealed and withstand applied or developed internal pressure by the expandable propellant incorporated with the contents to be sprayed, or by preapplied gas pressure in the container. The top opening of the container is closed by a permanently applied cap 11 inserted therein in the nature of a stopper and curled, as at 12, at its protruding periphery into interengaging retention with a curled rim 13 bordering the container opening. In making the assembly, a suitable sealing compound may be included between the curls of the cap and rim. The cap 11 is of general cup-shape with a cylindrical outer wall 14 and planar bottom wall 15, and has a re-entrant neck 16 coaxial with the outer wall but of less height axially. For convenience of description, orienting terms, such as top and bottom, are used in appropriate application to the position of parts as illustrated in the drawing, but without restricting the invention to necessarily having to be in the erect position shown. At the top of said neck 16 is a cross-wall 17 here shown as flat and in a plane parallel to aforesaid planar bottom wall 15. Cap or cup 11 may appropriately be stamped or drawn from sheet aluminum of adequate strength to constitute mounting for the valve assembly and to withstand deformation in use.

The valve assembly includes a hollow cylindrical member which will be herein referred to as valve-tail 18 and which is of rigid character made, for instance, of brass, steel or other material. The upper end portion 19 of this valve-tail 18 is of upwardly outwardly flaring bell formation providing a circular upper terminal rim. The

2

bottom end of valve-tail 18 has an in-turned flange 20 which leaves a hole 20' therethrough for admission of fluid from the container into the said valve-tail.

Said upper rim of bell 19 of the valve-tail 18 has a diameter agreeable to the internal diameter of cup neck 16 and is inserted therein with said rim proximate to the cylindrical neck wall. The valve-tail 18 is accordingly located coaxially with the cup and cup neck, and having greater length than said cup neck, depends a considerable distance below the bottom wall 15 of the cup. Within said neck 16 of the cap and compressed between the upper rim of said bell 19 of the valve-tail and the top cross-wall 17 of the cup neck 16, is valve-gasket 21 of suitable material, of which buna and neoprene are examples. Permanent retention of the bell or flare of the valve-tail is obtained by pinching, as at 22, the wall of neck 16 under the outer peripheral rim of the bell or flare. By virtue of the neck 16 being re-entrant in the cup, this pinch is very conveniently made by a suitable tool (not shown) that can be introduced in the open mouth of the cup.

Extending coaxially within and projecting upwardly from said valve-tail 18 is a hollow or tubular valve-stem 23. Within the body of the valve-tail the said valve-stem 23 has a peripheral bulge 24 which will act as a stop to limit upward movement of the valve-stem by engagement with the under face of valve-gasket 21. Said valve-stem is open only at its upper end and closed at its lower end. The valve-stem 23 has a lateral port 25 communicating from the exterior to the hollow interior of said valve-stem, said port being at a part of the valve-stem above the bulge 24 and at a location such that by sliding the valve-stem the port may be brought at one or upper position within the confines of the valve-gasket 21 and in another or lower position below the said gasket. The gasket hugs the valve-stem and constitutes a seal against passage of fluid past the same between it and the valve-stem. It may also be here noted that the same gasket also effects a seal at its margin by compression of the rim of bell 19 thereagainst.

When the port 25 is within the confines of gasket 21, it is sealed thereby against passage of fluid therethrough, thus utilizing the gasket for a third function, but when the port is below the gasket it provides passage from the interior of the valve-tail 18 to the interior of the valve-stem 23. The open upper end of said valve-stem communicates with a passageway 26 in an operating button 27 on the upper end of the valve-stem, said button having an outlet orifice 28 in communication with said passageway so that contents from valve-tail 18 will discharge from the said orifice. When the valve-stem is at the upper end of its stroke, which is its normal position, limited by engagement of bulge 24 with the valve-gasket 21, port 25 is located within the gasket between the top and bottom planar faces thereof, which therefore seals the port and prevents flow of fluid from the valve-tail to the interior of the valve-stem and therefore no discharge takes place. In order to maintain the valve-stem in its upper or normal position, except when manually depressed, a spring 29 encircles the lower portion thereof and is under compression by bearing at its upper end against bulge 24 and bearing at its lower end against flange 20 of the valve-tail. A dip tube 30 has its upper end applied on the outside of the valve-tail and goes to the bottom of the container as usual to supply fluid to the valve-tail until the container is substantially empty.

I claim:

1. An aerosol valve construction for dispensing fluid from a container, comprising in combination a closure cap for the container, having a reentrant upwardly-extended neck provided with an apertured transverse top wall to accommodate a valve stem in the aperture there-

of; a valve gasket in the form of a flat washer, seated in the neck against said top wall; a valve tail comprising a tubular, circular housing member received in and depending from said reentrant neck, said member having a flared bell and disposed in the neck and constituting a valve-gasket clamping means, said end presenting a sharp circular edge of substantially the same diameter as the outer periphery of the gasket and constituting the sole engagement of the valve tail with the valve gasket, said clamping end being devoid of flats of appreciable area whereby it engages the gasket with virtually a thin-line, circular contact and is partially embedded therein to effect a tight seal therewith; detent means on the reentrant neck, engaged with the said bell end to retain the valve tail in the neck with the sharp circular edge engaged under pressure with the outer peripheral por-

tion of the gasket; and a hollow valve stem disposed in the valve tail and projecting through the gasket and top wall, said stem being longitudinally movable and having a valve member engageable with the gasket to control the passage of fluid through the valve tail.

2. A valve construction as in claim 1, wherein the bell end cures outward from the body of the valve tail to the said sharp circular edge.
